UNITED STATES PATENT OFFICE.

MARTIN C. SCHWAB, OF BALTIMORE, MARYLAND, ASSIGNOR TO GRAVITY CONVEYOR COMPANY, A CORPORATION OF NEW YORK.

PACKAGE-CONVEYER.

No. 868,020.

Specification of Letters Patent.

Patented Oct. 15, 1907.

Application filed January 23, 1905. Serial No. 242,406.

To all whom it may concern:

Be it known that I, MARTIN C. SCHWAB, a citizen of the United States, and a resident of Baltimore, in the State of Maryland, have invented certain new and useful Improvements in Package-Conveyers, of which the following is a specification.

My invention relates to an improved package conveyor or chute which is so arranged that the parcels which pass through it may be discharged at any desired floor.

It includes certain other novel features which will be described in the following specification and pointed out in claims.

Like characters of reference designate similar parts in all the figures of which

Figure 1 is a side elevation, partly in section, of a package conveyor of the spiral gravity type with my invention applied thereto. Fig. 2 is a plan view of a section taken through the conveyor on the line A-B of Fig. 1, and shows a modification of one part of my invention. Fig. 3 is a sectional elevation of part of the conveyor showing a modification of one part of my invention more in detail. Fig. 4 is a plan view of the parts shown in Fig. 3. Figs. 5 and 6 are details of certain parts which will be fully explained later.

Referring to the drawings, 10 designates a spiral chute or conveyor which comprises an outer shell 11, an inner tube 13 between which is situated a spiral conveying surface 12. The various landings or floors which are connected by this conveyor are designated by 20, 30, 40, 50 and 60. At each of these floors, openings 21, 31, 41, 51 and 61 are provided which are preferably slightly above the floor level and which afford communication between the landings and the interior of the conveyor 35 and through which packages may be placed in the conveyor. These openings may be closed by doors 32, 42, 52 and 62. Other openings for discharging packages from the conveyor may be provided above the surface of the spiral at the various floors or at any desired points 40 and such openings are designated in the drawings by 23, 33, 43 and 53. Troughs or chutes 24, 34, 44, and 54 may be placed opposite these openings to guide the parcels which are discharged through them to the desired location. Pivoted shelves 25, 35, 45, and 55 are 45 situated near these openings, preferably in such position as to form a continuation or extension of the troughs into the conveyor in the nature of bridges. These pivoted shelves or bridges are normally raised above the spiral or the carrying surface of the conveyor, in the 50 position shown at 25, 45, and 55, so that they do not obstruct the passage of parcels through the conveyor. On the outside of the conveyor and rigidly attached to the shafts which carry the pivoted shelves are arms 26, 36, 46 and 56 to the outer ends of which vertical rods 27,

37, 47 and 57 are connected. By means of these vertical rods and their connections which have just been described, a person on any landing or floor may move a pivoted shelf on any one of the floors below. These shelves are adapted when thus moved to rest upon the surface of the spiral 12 in the manner shown at 35 so as to form bridges between the troughs and said surface. In Fig. 2 is shown a sectional plan view of this part of the conveyor, the section being taken on the line A-B of Fig. 1. A shelf 35 is shown hinged to the inner end of the trough 34, its free end being adapted to make contact with the spiral surface as clearly shown in Fig. 1. It is obvious that any packages which may be descending through the conveyor from above will be caught by this shelf and guided onto the chute or trough 34 which will carry it to the desired place.

Figs. 3 and 4 show a modification of construction in which case instead of using the pivoted shelves which have been described, a part of the spiral itself is made movable. This part is designated by 12'. It is pivoted as are the shelves before described and may be moved by means of an arm 36'. Ordinarily the part 12' constituting a bridge or shelf rests upon the surface of the spiral 12, so that it has no effect upon the usual operation of the conveyor. An opening 33 is placed as before, above the surface of the spiral. Now when the 80 movable part 12' of the spiral is raised to such a position as that indicated in Fig. 3, the parcels which are descending through the conveyor from above will be guided by it up onto the chute 34 and thus delivered at the desired place.

In the operation of this apparatus it is highly desirable to prevent interference between the different floors; that is, to have the apparatus so arranged that when a person on one floor has operated a shelf at the particular landing at which he desires to have parcels 90 delivered, no one can operate any of the other shelves until the first person is through. For this reason I have provided a non-interference or inter-locking device which I will now describe.

All of the vertical rods 27, 37, 47 and 57 pass through 95 an inter-locking device 70. They are provided near their upper ends with stop collars 28, 38, 48 and 58 which limit their downward movement by coming in contact with some stationary pieces through which the rods pass. In the drawings this stationary piece is shown 100 as the top of the frame of the inter-locking device. The interlocking device itself comprises a housing 71 which is provided with a horizontal hole 73 in which are placed a number of loose sliding bolts or locking pieces 72. A number of vertical openings are provided in the housing 71, one for each of the vertical rods, and these openings act as guides for enlarged portions 29, 39, 49 and 59 which are either a part of or are

attached to the vertical rods 27, 37, 47 and 57. These enlarged portions are wedge-shaped at their upper ends and are adapted to be moved between the sliding bolts or locking pieces whenever the vertical rods to which they are attached are raised. The movement of the sliding bolts or locking pieces is limited as the ends of the horizontal hole in which they are placed are closed and as their combined length plus the width of one of the enlarged portions of the vertical rods is approximately equal to the length of the horizontal hole. It is evident then that whenever one of the vertical rods is in its raised position so that its enlarged portion is between two of the sliding bolts or locking pieces, that the entire length of the horizontal hole 73 is filled. It is therefore impossible to raise two of the vertical rods at the same time. As these vertical rods are attached to the pivoted shelves, or to the pivoted portion of the spiral at the various landings, this arrangement provides an effective device for preventing the operation of any of these pivoted shelves while one of them is in use.

It should be noted that the position of the stop collars 28, 38, 48 and 58 will determine at any time what particular shelf or slide, as for example that designated 25 35, has been moved into engagement with the spiral 12. The position of any shelf or slide with respect to the spiral may also be determined by noting the relative positions of the rods 27, 37, 47 and 57. By reason of the interlocking device, only one slide can be operated at a time, so that if it is attempted to operate the rods, the rod connected to the slide which is in contact with the spiral may be easily found. This is because the rod connected to the slide in contact with the spiral is the only one that can be operated, and only until after it 30 35 has been operated to remove the slide connected thereto from the spiral, can one of the other rods be operated.

Obviously, the position of the arms 26, 36, 46 and 56 will at any time show whether or not the slide connected thereto is in contact with the spiral. For instance the position of the slides at the lower floors may be easily determined by attempting to operate said rods, only the rod connected to the slide which is in contact with the spiral being movable at this time, by reason of the interlocking device, as hereinbefore 40 45 explained. Obviously, many modifications may be made in the details of construction and arrangement of parts with reference to the indicating feature, as well as other features of my invention, without departing from the spirit and scope thereof.

50 Gravity conveyers of the type here shown are in common use. They are arranged to carry parcels from a point above to a common point beneath. Manifestly the present invention greatly increases the usefulness of such conveyers as by it one is able to place parcels in the conveyer and have them delivered at any one of several desired points.

I have shown a few constructions as illustrative of my invention, but it is capable of many modifications.

What I claim and desire to secure by Letters Patent 60 is:

1. The combination with the conveyer having a conveying surface, extending above and below an opening in the conveyer of movable means for connecting the opening in said conveyer with the conveying surface.

2. The combination with a conveyer having a conveying surface, extending above and below an opening in the conveyer of a device for connecting an opening in said conveyer with the conveying surface and means for applying said connecting device. 65

3. The combination with a conveyer having a conveying surface, extending above and below an opening in the conveyer of a bridge for connecting an opening in said conveyer with the conveying surface, and means for applying said bridge. 70

4. The combination with a gravity conveyer having a conveying surface, extending above and below an opening in the conveyer of a bridge, and means for applying said bridge to connect said conveying surface with an exit opening. 75

5. The combination with a gravity conveyer provided with a conveying surface, of a pivoted bridge, and means outside of the conveyer for moving said bridge to connect said surface with an exit opening. 80

6. The combination with a gravity conveyer, of a plurality of bridges, and means outside of the conveyer for moving said bridges to connect the conveyer with exit openings. 85

7. The combination with a gravity conveyer provided with a conveying surface, extending above and below an opening in the conveyer of a plurality of bridges connected thereto, and means for applying said bridges to connect said surface with exit openings in the conveyer. 90

8. The combination with a gravity conveyer having a conveying surface, extending above and below an opening in the conveyer of a plurality of bridges pivotally connected to the conveyer, and means for moving said bridges to connect or dis-connect said conveying surface with said openings. 95

9. The combination with a gravity conveyer having a conveying surface, extending above and below an opening in the conveyer of a pivoted bridge for each of a plurality of exit openings, and individual means for operating the bridges to connect or dis-connect the conveying surface with the openings. 100

10. The combination with a gravity conveyer having a plurality of exit openings, a pivoted bridge for each exit opening, and individual means connected to said bridges and extending to the outside of the conveyer for moving said bridges. 105

11. The combination with a gravity conveyer having a conveying surface, of a trough at or near an opening in said conveyer, and movable means for connecting said surface with said trough. 110

12. The combination with a conveyer having a conveying surface, of a plurality of troughs at different elevations adjacent openings in said conveyer, bridges connected at or near said openings, and individual means for operating said bridges to connect or dis-connect them between said conveying surface and said troughs. 115

13. The combination with a gravity conveyer provided with a plurality of exit openings, of movable bridges at or near said openings, and individual means extending to a common point for operating said bridges to move the same. 120

14. The combination with a gravity conveyer having a conveying surface, of movable bridges, troughs at or near exit openings in said conveyer, and individual devices extending to a common point within reach of the operator for moving said bridges to connect or dis-connect said conveying surface with any one of said troughs. 125

15. The combination with a conveyer having a conveying surface, of bridges for tangentially connecting said surface with exit openings at different elevations, and independent means extending to a common point for moving said bridges. 130

16. The combination with a gravity conveyer, of troughs at openings in said conveyer above adjacent edges of said conveying surface, movable bridges, and independent means extending to a common point for moving said bridges to connect or dis-connect the conveying surface with said troughs. 140

17. The combination with a gravity conveyer having a

- conveying surface, of a trough at or near an exit opening in said conveyer, a movable bridge, and means for moving the same to connect the upper portion of the surface with the trough.
- 5 18. The combination with a gravity conveyer having a spiral surface, of landings, said conveyer being provided with a feed opening and an exit opening at each landing, movable bridges for connecting or dis-connecting said spiral surface with said exit openings, and individual means extending to the top landing for operating at any landing any one of the bridges at a lower landing to connect or dis-connect said spiral surface with an exit opening.
- 10 19. The combination with a gravity conveyer having a conveying surface, a plurality of bridges at or near corresponding openings in said conveyer, individual means for connecting or dis-connecting said conveying surface with said openings, and means for preventing the operation of any other bridge upon the operation of one selected bridge.
- 15 20. The combination with a gravity conveyer having a conveying surface and openings at different elevations, movable bridges for connecting said surface and openings, individual devices extending to a common point for operating said bridges, and locking mechanism for preventing the operation of other bridges upon the operation of any selected bridge.
- 20 21. The combination with a gravity conveyer having a conveying surface, of pivoted bridges for connecting or dis-connecting said surface with openings at different elevations, individual devices extending to a common point for operating said bridges, cams at the ends of said devices, and sliding locking devices co-acting with said cams for permitting the operation of only one of said bridges 30 at a time.
- 25 22. The combination with a gravity conveyer having a conveying surface, of pivoted bridges, for connecting or dis-connecting said surface with openings at different floors, levers secured to said bridges and pivotally connected to said conveyer, individual rods extending up-wardly from said levers, cams on the upper ends of said rods, and sliding rods with conical ends arranged to co-operate with said cams for preventing the operation of other bridges after the operation of one selected bridge.
- 30 23. In a device of the class described, the combination with a spiral slideway, of a plurality of discharge-slides at the various floors arranged to be moved into contact with the slideway to deflect material moving on the same, and means at the floors above each of said discharge-slides for controlling the same. 45
- 35 24. In a device of the class described, the combination with a spiral slideway, of a plurality of discharge-slides at the various floors arranged to be moved into contact with the slideway to deflect material moving on the same, means at the floors above each of said slides for controlling the same, and means for indicating the position of said discharge-slides. 50
- 40 25. In a device of the class described, the combination with a tube and a spiral slideway therein, of pivoted discharge-slides forming doors which close suitable openings of the tube at various floors, said discharge-slides being adapted to be swung down in contact with the slideway to deflect material moving thereon and means capable of being operated from the various floors above each of said discharge-slides to control the same. 60
- 45 26. In a device of the class described, the combination with a spiral chute, of devices for deflecting material therefrom at the various floors above the basement, and means capable of being operated from the various floors above each of said devices for controlling the same. 65
- 50 27. In a spiral gravity conveyer, the combination with an outer shell and an inner core, of an interposed spiral blade, and an inwardly swinging door above the spiral and conforming substantially to the inclination thereof. 70
